UNITED STATES PATENT OFFICE.

GEORGE C. BERRY, NOAH R. STEINER, AND LARKIN S. MYLER, OF AKRON,
OHIO.

DESIGN FOR A BUTTON-BADGE.

SPECIFICATION forming part of Design No. 30,167, dated February 14, 1898.

Application filed January 9, 1898. Serial No. 701,673. Term of patent 14 years.

To all whom it may concern:

Be it known that we, GEORGE C. BERRY, NOAH R. STEINER, and LARKIN S. MYLER, citizens of the United States, residing at 5 Akron, in the county of Summit and State of Ohio, have invented and produced a new and original Design for a Button-Badge, of which the following is a specification, reference being had to the accompanying drawings, forming a part thereof.

Figure 1 is a view of a badge-button enlarged, showing our design; Fig. 2, a sectional view taken at the line X X of Fig. 1.

As shown in the drawings, the leading or 15 material feature of our design consists of a hunter in conventional costume holding a gun with the butt on the earth and a dead deer lying adjacent to him. This is located in a

circle. The background shows a wood scene, and the whole engraved or otherwise ornamented. 20

It is apparent that this design is applicable to both clasp-buttons and studs and may be engraved on watch-charms and other ornaments. 25

Having described our invention, what we claim as new, and desire to secure by Letters Patent, is—

The design for a badge-button, as herein shown and described.

GEORGE C. BERRY.
NOAH R. STEINER.
LARKIN S. MYLER.

In presence of—

C. P. HUMPHREY,
C. E. HUMPHREY.
